UNITED STATES PATENT OFFICE.

EDWARD W. DURKEE, OF MASON, ILLINOIS.

WIRE-COILING MACHINE.

SPECIFICATION forming part of Letters Patent No. 291,500, dated January 9, 1884.

Application filed May 21, 1883. (No model.)

To all whom it may concern:

Be it known that I, EDWARD W. DURKEE, a citizen of the United States, residing at Mason, in the county of Effingham and State of Illinois, have invented certain new and useful Improvements in Wire-Coiling Machines, of which the following is a specification.

My invention relates to that class of wire-coiling machines in which the wire is pushed by suitable mechanism through a spiral groove, and thereby formed into a continuous spiral coil of any desired length.

The objects of my improvements are, first, to prevent the clogging of the wire in the coiling device; and, second, to provide improved means for accurately adjusting the relative position of the wire-guide and the coiling device. These objects I accomplish by means of the mechanism hereinafter described, and illustrated in the accompanying drawings, in which—

Figure 1 represents a perspective view of my machine. Fig. 2 is a plan of the wire-guide and the coiling device and adjustable supports therefor. Fig. 3 is an enlarged perspective view of the grooved cylinder forming part of the coiling device.

A casting, *a*, forms the frame of the machine. *b* *c* are friction-wheels, having on their peripheries, or a portion thereof, intermeshing cog-teeth. Said wheels are mounted on shafts *d* and *e*, having bearings in the frame *a*, the bearings of *e* being vertically movable in frame *a*, and held in position by a set-screw, *f*, and spring *g* at each end. The peripheries of wheels *b* and *c* are each provided with a groove, *h*, adapted to receive the wire passing between them. A hand-wheel, *i*, secured to shaft *d*, serves to drive the wheels *b* and *c*.

The machine thus far is similar in all respects to that shown in Letters Patent No. 273,483, granted to me March 6, 1883. In the coiling device there shown the spiral groove which forms the coil is on the exterior of a mandrel, and the wire is forced to follow said groove by a semi-cylindrical cap, smooth on its interior, and secured to the exterior of the before-mentioned mandrel. In all machines of this class of which I have any knowledge heretofore the spiral groove has been formed in the exterior of a mandrel, and va-

rious means have been used to cause the wire to follow the groove.

It has been found in practice that the normal tendency of the wire to move in a straight line against the confining-shell or semi-cylinder causes the interior of the confining-shell to wear in such a manner that the end of the wire, when starting in, is liable, particularly if the parts are not closely fitted, to leave the groove and be forced into the joint between the mandrel and its shell, and thereby clog and stop the machine and spoil the coil. In my present machine I remedy this difficulty by making the exterior of the coil-forming mandrel *j* smooth, without grooves. Upon said mandrel I slip a hollow cylinder, *k*, nicely fitted thereto, and which I secure thereon by a pin or set-screw, *k'*. The interior of cylinder *k* has one or more spiral grooves, *x*, formed therein, as shown in Fig. 3. Only one of said grooves is used at a time; but several are provided, so that when one becomes worn another may be used, as hereinafter explained. One end of cylinder *k* is notched or filed away at 75 the commencement of the grooves, as at *l*, so as to present a surface nearly at a right angle to the spiral line of the groove, for the purpose of properly introducing the wire. The normal tendency of the wire to move in a straight line 80 now causes the wire to press closely into and against the bottom of the groove, and there is consequently no tendency to get into the joint between the cylinder and mandrel. In my formerly-patented machine the wire-guide and 85 the coiling device were separately mounted in opposite sides of the frame, and it has been found difficult to properly adjust and maintain their relative positions. In my present machine a bar, *m*, is secured by a set-screw in 90 a socket, *n*, in frame *a*. The wire-guide *o* is passed through *m*, near the free end thereof, and is secured by a set-screw, *p*. The bar *m* and wire-guide *o* are each adapted to be adjusted by being turned or moved longitudinally in their sockets.

The wire-coiling device, instead of being secured in a socket in the frame, is secured in a casting, *r*, which is adapted to slide and turn on bar *m*, and which is secured in position on 100 said bar by a set-screw, *s*. The coiling device is secured in *r* at such an angle as to bring the

entrance to one of the grooves in cylinder *k* in exact line with the wire-guide *o*, the mandrel being adjustable longitudinally in *r*, and adapted also to be turned therein and secured in place by a set-screw, *t*. By this construction and combination of parts, the wire-guide and the coiler, when once set in relation to each other, may be removed from the machine and replaced, or may be properly adjusted to receive the wire from the wheels *b* and *c* without disturbing their relative adjustment. When one of the grooves in cylinder *k* becomes worn out, a new groove may be presented to the wire-guide by loosening set-screw *t* and turning the mandrel *j* and cylinder *k*.

The operation of my machine is as follows: The wire to be coiled is passed between wheels *b* and *c*, in groove *h*, the wheels being set suf-

ficiently near together to cause a strong friction on the wire. As the wire is drawn forward by the revolution of said wheels it is pushed through guide *o* into one of the spiral grooves in cylinder *k*, and is bent into the shape of said groove as it is pushed still farther forward, and issues in a continuous coil from the opposite end of the cylinder.

I claim as my invention—

In a wire-coiling machine, bar *m*, wire-guide *o*, casting *r*, mandrel *j*, and cylinder *k*, grooved as described, and all combined in the manner specified.

EDWARD W. DURKEE.
